Washing Machine

Patented Apr. 5, 1831

W. 5. 1851
6444X - Miller D. Mulford.
Letters Patent.

73

The Schedule referred to in these Letters Patent and making part of the same containing a description in the words of the said Miller D. Mulford himself of his improvement in the washing machine.

To all to whom these Presents shall come,
Be it known, that I, Miller D. Mulford of Bloomfield, in the County of Ontario & State of New York have invented a new & useful machine for washing clothes and that the following is a full and exact description of the operation and construction of such machine. The machine may be made in the form of a box or cylinder which is hinged on one side & placed in a frame & put in motion by hand, and the motion kept up, by spring and balance power, which will be more fully shown by the drawings accompanying this description. Figure 1, where the handles are put to take, holes to put the machine in motion, which handles are also necessary to strike the springs represented by figure 5, which springs help to keep the machine in motion, together with weights, which are in the box represented by figure 6, which make the balance power mentioned above. Figure 4, the standard, on which the box or cylinder is hung on just gears, fastened on each end of the box or cylinder. Figure 7, the sit or bottom of the frame. Figure 8, represents the end of the box in which the clothes are put. Figure 9, the shape of the standards, which are fastened inside of box or cylinder by tenons put thro' the centre of the bottom of the box or cylinder. Figure 10, the end of the box containing the weights and fastened to the end of the cylinder or box in which the clothes are. Figure 9, is where a pin is put through the standard into the board represented by figure 3, for the purpose of holding the machine in any position for taking out or putting the clothes into the box or cylinder.
